UNITED STATES PATENT OFFICE.

THOMAS W. DEROUSSE, OF PHILADELPHIA, PENNSYLVANIA.

DESIGN FOR MEDALS.

Specification forming part of Design No. 7,825, dated November 3, 1874; application filed October 22, 1874
[Term of Patent 2½ years.]

CASE B.

To all whom it may concern:

Be it known that I, THOS. W. DEROUSSE, of the city and county of Philadelphia, State of Pennsylvania, have invented a Design for a Centennial Medal, of which the following is a specification:

The nature of my design is fully represented in the accompanying drawings, to which reference is made.

Figure 1 is a front or obverse view of my medal, showing a fort and vessel, and is commemorative of the sinking of the British frigate Augusta. Above the vessel appears a scroll containing the words "Sunk 1777." This representation is surrounded by an ornamental scroll or border, outside of which, and between it and the outer rim of the medal, appear the words "The British Frigate Augusta, 64 Guns," and, in the same space, beneath the representation, the words "Capt. Reynolds." The reverse side: Fig. 2 represents, in relief, a Continental soldier on guard, and to the

right and left the figures "1776"—"1876;" above him, arranged in semicircular form, is the word "Centennial;" on the right and left appear sprigs of laurel and oak with their stems crossed at the bottom; and surrounding the whole is an ornamental scroll similar to that in Fig. 1, between which and the outer rim is a space containing the words "Sunk in Action on River Delaware at Red Bank, N. J., Oct. 23rd, 1777."

This medal may be composed of metal, plaster, gutta-percha, or any other substance usually employed in the manufacture of medals; and it may be of any convenient size.

What I claim as my invention, and desire to secure by Letters Patent, is—

The design for a medal, substantially as described and shown.

THOS. W. DEROUSSE.
